[57] ABSTRACT

A sinker for use in warp knitting machines. The lower portion of the sinker throat has a protrusion formed therein which functions as a knock-over step. The throat is extended beyond this step by a slot. The old stitches may slide off into this slot after knock-over, to reduce wear and stress on the threads.

SINKER FOR WARP KNITTING MACHINE

This invention relates generally to warp knitting machines, and more specifically to the sinkers utilized in such machines.

In the sinkers previously known in the art, the throats thereof are defined as a U-shaped opening, the termination of the "U" serving as the effective stop for movement of the stitches during the knitting cycle. This prior art configuration leads to certain consequences. On the one hand the thread ends which run between the wales even after knock-over, are greatly affected during the upward movement of the needles by contact with the terminal step of the said opening. Furthermore, because the needle shafts become thicker toward the base ends thereof, the space between the shafts and the sinker plates is comparatively small, so that only thread material of rather narrow gauge can be worked without interference.

The affect upon the threads running between the wales at the throat terminal end of the aforementioned sinkers, may be lessened to a certain extent by moving the sinkers slightly backward during the upward thrust of the needles. However, during this additional movement, waste of drive power of the warp knitting machine is increased. It is also known to use sinkers for warp knitting machines which have no terminal throat step, but serve merely to hold down the beginning of the goods. Unfortunately, using machines which are equipped with sinkers of this type, only a comparatively inexact stitch pattern can be produced, since the old stitches are not sufficiently supported at the knock-over point.

The foregoing disadvantages of the known sinkers are avoided, in accordance with the present invention, by means of a construction wherein a protruberance formed in the lower portion of the sinker throat functions as a knock-over stop (in analogy to the similar function formed by the terminal end of the throats of the prior art), and by extending the throat beyond the angularly by a slot. This lengthening of the sinker throat permits the old stitches to slide off and expand into the said slot after the knock-over, during the subsequent upward thrust of the needles which occurs during development of the new stitches.

The new stitches are thus free to move sideways in the realm of the lengthened throat, so that the friction on the needle shafts is reduced and at the same time thicker thread material may be utilized.

The invention is diagrammatically illustrated by way of example, in the drawings appended hereto, in which:

FIG. 1 is a plan view of a sinker in accordance with the present invention having a step-formed angularity formed at the bottom portion of the throat thereof; and

FIG. 2 is a plan view of a further sinker in accordance with the present invention, having a nose-formed angularity in the throat thereof.

Sinker 1 in the embodiment of both FIGS. 1 and 2 has at the forward end thereof a sinker head 2, and a belly portion 3 which serves to knock-over the old stitches and forms a portion of the lower edge of the sinker throat 4.

Throat 4 is defined on its upper surface by the sinker nose 5.

In the embodiment of the invention seen in FIG. 1, a protruberance is formed at the lower edge of the sinker throat. The angularity is more specifically defined by step 7. Adjacent to the angularity 6, the throat 4 is extended by a slot 10 extending into the upper part of the throat.

In the embodiment of FIG. 2 the protruberance 6 comprises a nose 8. Beyond such protruberance the throat is again extended by a slot 10a. The dotted line 9 illustrates the maximum backward position of a needle (not illustrated), which demonstrates how the threads can expand into the enlarged throat at slots 10 or 10a.

While the present invention has been set forth in terms of specific embodiments thereof, it will be understood in view of the instant teaching, that numerous variations are now enabled to those skilled in the art, which variations yet reside within the scope of the present teaching. Accordingly the invention is to be broadly construed, and limited only by the scope and spirit of the Claims now appended hereto.

I claim:

1. A sinker for a warp knitting machine having a protruberance angle in the bottom portion of the throat thereof, said protruberance functioning as a knock-over stop during the knitting cycle, and a slot portion formed at said throat beyond said protruberance, for enabling expansion of stitches beyond said protruberance after said knock-over.

2. A sinker in accordance with claim 1 wherein a nose protrudes from the throat formed of said slot.

3. A sinker in accordance with claim 1, wherein said protruberance comprises a step formed at said throat portion.

4. A sinker in accordance with claim 1, wherein said protruberance comprises a nose-like portion.
